UNITED STATES PATENT OFFICE.

ERIC EARL HOUSTON, OF ASBURY PARK, NEW JERSEY.

COVER FOR GARBAGE-RECEPTACLES.

1,233,361.

Specification of Letters Patent. Patented July 17, 1917.

Application filed September 11, 1916. Serial No. 119,532.

To all whom it may concern:

Be it known that I, ERIC E. HOUSTON, a citizen of the United States, residing at Asbury Park, in the county of Monmouth and State of New Jersey, have invented certain new and useful Improvements in Covers for Garbage-Receptacles; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in covers for garbage and other receptacles and means for securely locking the cover in place and so constructed that it may be easily and quickly removed and replaced, when desired.

The present invention consists of a simple and efficient device of this nature, having various details of construction, combinations and arrangements of parts which will be hereinafter fully described, shown in the accompanying drawings and then specifically defined in the appended claims.

I illustrate my invention in the accompanying drawings, in which:—

Figure 1 is a top plan view of the cover.

Fig. 2 is a vertical sectional view through the same as applied to a receptacle.

Fig. 3 is an edge view.

Reference now being had to the details of the drawings by numeral, 1 designates a receptacle having a beading 2 about the marginal edge thereof, and 3 is a cover having a flange 4 which has a beading 5 about its marginal edge. It will be noted upon reference to Fig. 2 that, when the cover is adjusted in place upon the receptacle, a slight space intervenes between the flange and the circumference of the receptacle for a purpose which will presently be described.

Mounted to have longitudinal movements upon the cover are two bars 6, parallel to each other and spaced apart and guided in their longitudinal movements by the straps 7 which are fastened to the cover. The inner end of each bar 6 is turned to form an eye 8 and is pivotally connected to a handle 9, journaled on the top underneath the strap 10. The portion of the handle, it will be noted, on which the inner ends of the bars 6 are pivoted is similar in

shape to a crank shaft and so arranged that, when the handle is rocked, the two bars will be moved in opposite directions.

A handle holding member, designated by numeral 11, is fastened at its upstanding portion and is resilient and is grooved as at 12 for the reception of the swinging portion of the handle to hold the same in a position parallel to the cover when in a locking position.

Upon reference to Fig. 2 of the drawings, it will be noted that said bars are bent in the manner shown and each extends through a slot 14 formed in the flange of the cover and each outer end of the bar is T-shaped as at 15. The inner face of the flange of the cover at points diametrically opposite is provided with a recess 16 of the shape and size adapted to receive the T-shaped ends 70 15 of said bars when the latter are in unlocked positions and, when seated in said recesses, it will be noted that the outer faces of the T-shaped ends will be flush with the inner surface of the flange, thus allowing the 75 cover to be moved without interference with the beading 2.

The operation of my invention will be readily understood and is as follows:—When it is desired to place the cover upon the receptacle, the handle is swung to an upright position or in a plane at right angles to the cover, which movement will throw the T-shaped ends outward and away from the circumference of the receptacle, the cover 90 being placed over the receptacle and, by swinging the handle down to a horizontal position, the two T-shaped ends will be thrown against the circumference of the receptacle and underneath the beading 2. As 95 the handle is swung to a horizontal position, it will automatically engage the groove in the handle holding member which will hold the bars in locked relation.

What I claim to be new is:—

1. In combination with a receptacle having a beading about its upper edge, a flanged cover fitting over the receptacle, longitudinally movable bars mounted upon the cover, a swinging handle having pivotal connection with the inner ends of said bars and adapted to move the same simultaneously in opposite directions, the ends of said bars being T-shaped and adapted to engage underneath the beading of the receptacle when the bars are moved toward each other.

2. In combination with a receptacle having a beading about its upper edge, a flanged cover fitting over the receptacle, longitudinally movable bars mounted upon the cover, 5 a swinging handle having pivotal connection with the inner ends of said bars and adapted to move the same simultaneously in opposite directions, the ends of said bars being T-shaped and adapted to engage underneath the beading of the receptacle when 10 the bars are moved toward each other, and means for holding the bars in locked relation.
3. In combination with a receptacle having a beading about its upper edge, a flanged cover fitting over the receptacle, longitudinally movable bars mounted upon the cover, a swinging handle having pivotal connection with the inner ends of said bars and 15 adapted to move the same simultaneously in opposite directions, the ends of said bars being T-shaped and adapted to engage underneath the beading of the receptacle when the bars are moved toward each other, and 20 25 a resilient handle holding member mounted upon the cover and adapted to receive the handle to hold the same in a locked relation.
4. In combination with a receptacle having a beading about its upper edge, a flanged cover fitting over the receptacle, longitudinally movable bars mounted upon the cover, 20
- a swinging handle having pivotal connection with the inner ends of said bars and adapted to move the same simultaneously in opposite directions and provided with angled portions, parts of the bars movable through said slots in the flange of the cover and having portions adapted to engage underneath said beading when the bars are at their inner limits, and means for holding 35 the bars in locked relation. 40
5. In combination with a receptacle having a beading about its upper edge, a flanged cover fitting over the receptacle, longitudinally movable bars mounted upon the cover, 45 a swinging handle having pivotal connection with the inner ends of said bars and adapted to move the same simultaneously in opposite directions and provided with angled portions, parts of which are movable 50 through slots in the flange, the outer ends of the bars being T-shaped, the inner surface of the flange having diametrically opposite recesses to receive said T-shaped ends when the bars are at their outer limits. 55

In testimony whereof I hereunto affix my signature in presence of two witnesses.

ERIC EARL HOUSTON.
